United States Patent Office

Des. 185,395
Patented June 2, 1959

185,395

AIRCRAFT

John J. Sullivan, Norfolk, Va.

Application October 1, 1956, Serial No. 43,165

Term of patent 14 years

(Cl. D71—1)

Figure 1 is a perspective view of an aircraft embodying my new design.

Fig. 2 is a top or plan view of the aircraft shown in Fig. 1.

Fig. 3 is a front view of the aircraft of Figs. 1 and 2.

I claim:

The ornamental design for an aircraft, as shown.
